MILLING MACHINE AND METHOD

Theodore S. See, Hammond, Ind., assignor to
La Salle Steel Company, Chicago, Ill., a corpora-
tion of Delaware

Application February 10, 1948, Serial No. 7,372

2 Claims. (Cl. 90—15)

1

This invention relates to a new and improved method of milling metal work pieces and to a new and improved machine capable of practicing the method. The term "milling," as employed herein, indicates a planing action by a cutter on metal.

Heretofore, in the milling of steel work pieces, such as bars and the like, it has been common practice to employ a single point tool, held in a stationary position, and to rotate the bar, while at the same time feeding it lengthwise, to cause the tool to progress from one end of the bar to the other. Such an operation, while extensively used, is subject to the fundamental objection that it is slow and laborious. That the operation must be slow is necessitated by the fact that the cutting tool is constantly in contact with the metal and the chip being removed from the bar constantly flows over the tool thereby tending to heat and wear it unduly. Wearing or chipping of the tool results, of course, in shut down of the machine and regrinding of the tool. If increased speeds are employed in conjunction with such a cutting tool, increased wear and deterioration results, necessitating more frequent shut downs and regrindings.

In milling flat metal surfaces on the other hand, as described in a series of articles appearing in the 1947 issues of Iron Age, it has been customary to employ what is termed a "face cutter" in which a plurality of blades made of high speed cutting steel or carbide are mounted in a cutter body, by means of wedges and screws; and the cutter is then rotated and moved over the face of the work piece in such a manner that all of the blades are constantly in contact with the work. Here again the chip load on each blade is substantial and the operation is again subject to the fundamental objection that it is slow and laborious. In computing the work speed of a cutter of this type it has been customary to refer to the "surface foot rate" which is computed by employing the equation:

$$\pi d \times R. P. M. = S. F. M.$$

in which d is the diameter of the cutter, in feet; and R. P. M. represents the speed of rotation of the cutter, and S. F. M. represents the surface foot rate expressed in feet per minute. Heretofore in milling steel and steel alloys it has been the understanding of those skilled in the art that with the employment of high speed steel cutters the milling operation had to be performed at surface foot rates substantially below 500 feet per minute and with carbide cutters at surface foot

2

rates substantially below 1000 feet per minute. It was the discovery of the so-called "hard metals," such as tungsten carbide and other sintered carbide materials including tungsten titanium carbide that permitted the successful milling of steel and its alloys, particularly in the heat-treated state, at speeds higher than those employed with high speed steel tools.

With the foregoing desiderata in mind, the present invention has for an important object thereof, the milling of steel and alloy steels at speeds substantially in excess of those heretofore employed and previously considered possible. Whereas the art teaches that the speed of the cutter and the rate of movement of the cutter blade must be limited in order to obtain the best results, it has now been discovered that through the employment of speeds vastly in excess of those previously deemed possible the life of the cutter is prolonged, improved work finishes are obtained, the wear on the cutter is reduced to the point where it is practically negligible and the time required to perform a given piece of work is sharply reduced to a minimum. The practice of this new method is intimately associated with the shape and construction of the cutter itself for it must be appreciated that not all cutters, of any and all designs, will operate successfully at these vastly increased speeds. Thus it has been discovered that the cutter, made of hard metal such as alloys of carbides, borides, nitrides, or silicides, must be provided with a maximum or a near maximum number of teeth or cutting blades positioned in close proximity with one another, whereby the pitch, i. e., the distance from one cutting edge to the next adjacent cutting edge is reduced to a minimum or near minimum, and the cutter is rotated at speeds greatly in excess of those heretofore employed. Accordingly, in practicing the present invention, the screws and wedges of the prior art cutters are eliminated because they require the teeth to be spaced too far apart to permit their use for the purpose intended.

As disclosed herein the teeth, formed of high speed steel, for operation at lower speeds, but substantially above the speed range previously employed in milling steel, particularly steel and steel alloys, or preferably of so-called hard metal or of sintered carbide materials are ground or cut into the cutting face of a monolithic cutter in such a manner as to produce a low or minimum pitch and a maximum or near maximum number of teeth in the peripheral face of the cutter. Cutters of this character, operating at high

speeds, at rates far in excess of those heretofore employed, have been discovered capable of increasing the rate of milling on a bar of steel from, for example, 90 inches per minute to 900 or even 1800 inches per minute. The chip load on the teeth is maintained at reasonable values effective to insure a satisfactory cutter life and fatigue in the cutter is eliminated. Employing such cutters at these extraordinarily high speeds will, in many instances, result in a noiseless operation in which the cutting action takes place too rapidly to be visible to the naked eye and only by the accumulation of chips and the improved appearance of the metal can it be observed that the milling operation is actually taking place.

As indicated above, the present invention has for another important object thereof, the provision of an improved machine capable of performing the improved method. As disclosed herein the invention is embodied in a machine for turning metal bars, in which the bar, rigidly held against radial vibration is fed lengthwise between a plurality of cutters constructed in accordance with the principles recited herein, and the cutters are constructed and arranged to rotate about their own axes at the high speeds mentioned and at the same time revolve bodily, in a planetary motion around the bar being milled. It will be appreciated however that the method of the invention may be incorporated in machines of other design and construction without departing from the spirit of the invention as set forth in the appended claims.

Other objects and features of the invention will become apparent from a reading of the following specification in the light of the accompanying drawings, in which,

Figure 1 is a front plan view of a machine constructed in accordance with the present invention;

Figure 2 is a view similar to Figure 1, showing a suction fan applied to the machine of Figure 1 for the purpose of chip disposal;

Figure 3 is a diagrammatic end view of the machine showing the arrangement of the suction fans;

Figure 4 is a view in section of the cutter assembly;

Figure 5 is a view in section taken substantially along the line 5-5 of Fig. 1 showing the cutter and motor mountings;

Figure 6 is a detail view, in section, of the adjustable work-piece bearing taken substantially along the line 6-6 of Fig. 1;

Figure 7 is a detail, top plan view, in section, of the bearing shown in Figure 6; and

Figures 8 to 12 inclusive are views of cutters.

As shown in the drawings, the reference numerals 10 and 12 indicate standards arranged to support the milling machine which is indicated generally by the numeral 14 (Figure 1). Extending through openings formed in the standards 10 and 12 are a plurality of hollow supporting shafts 16 and 18 provided with hub portions 20, 22 having flared, web-like members 24, 26 formed integrally therewith and joined at their opposite extremities to a hood or casing 28 within which the cutter assembly is located.

In general, the cutter assembly comprises, as shown in Figures 1, 4 and 5, a pair of electric driving motors 40, 42 located at the left, or entering, end of the machine, as shown in Figure 1, and a second pair of driving motors 44, 46 positioned at the right or exit end of the machine.

These motors, which are provided for the purpose of rotating the cutters about their own axes, are pivotally mounted upon the hood or casing by means of pins 50 and are each provided with a driving member 52 having driving engagement with driven member 54 (Fig. 4) keyed to pins 56 which form a part of the shaft assemblies for supporting milling cutters 60. Removable couplings 62 are inserted in the cutter shaft assembly to permit ready removal of the cutters from the machine for purposes of grinding or replacement by cutters of other shapes or sizes.

The cutters 60 are keyed to spindles 64 which form the central portion of the cutter shaft assembly and are held in position by means of lock nuts 66 having screw threaded engagement with the spindles.

As shown in Figures 1, 5 and 6, the hood or casing 28 is S-shaped in cross-section to provide a plurality of oppositely facing trough-like members or pockets into which the motors 40, 42 and 44, 46 are mounted. In accordance with the invention the S-shaped hood or frame 28 is mounted for rotation within the standards 10, 12 and to this end a driving member 71, which is shown as comprising a chain or belt, is connected with a suitable source of power (not shown). Thus, in operation, the casing or frame 28 rotates, carrying with it the motors and the cutter assemblies, as a result of which, it will be understood, the cutters, driven by the motors 46, 42 and 44 are caused to rotate, or spin, about their own axes and simultaneously move in a planetary path around the work piece or bar A which extends lengthwise, centrally, through the machine.

In order to provide suitable support for the bar A during the machining or milling operation, and to prevent undue vibration of the bar with respect to the cutters, bearing or supporting assemblies indicated generally by the reference numerals 70, 72 in Figure 1, and shown more specifically in Figures 6 and 7, are provided. As shown in Figure 1, one such bearing or supporting assembly is located adjacent each end of that portion of the bar being milled and, as shown in Figures 6 and 7, each assembly comprises a plurality of roller bearings 74, 76 having engagement with the bar or work piece A at spaced points. The bearings 74, 76 are mounted in a housing 78 that is slidably mounted by means of mounting blocks 80 on the frame or casing 28 of the machine and thereby revolve with the frame or casing about the bar or work piece A. An adjusting screw 82 equipped with a hand wheel 84 is provided for the purpose of moving the housing 78 to the right or to the left of the position shown in Figure 6. The rolls 74 are mounted on the housing 78 and thus movement of the housing results in movement of the roller bearings 74 towards or away from the axis of the work piece A. In order to move the cooperating bearings 76 towards or away from the axis of the work piece, independently of the bearings 74, to accommodate bars of various diameters, the said bearings 76 are mounted, within the housing 78, on a sleeve-like member 88 that is arranged to slide back and forth within the housing. The sleeve 88 is pivotally mounted on the extremity of an arm 90 arranged to extend through a hollow, tubular member 92. The sleeve 88 and the arm 90 are urged to the left of the position shown in Figure 6 by means of a compression spring 94, but may be adjusted in either direction, to the right or left, by means of a hand wheel 96.

having screw-threaded engagement 98 with the arm 90. Thus, rotation of the hand wheel in one direction will draw the arm 90, the sleeve 88 and the roller bearings 76 away from the work piece A, whereas rotation in the reverse direction will permit the arm 90, under influence of the spring 94, to move in the opposite direction, towards the axis of the work piece. A supplemental adjustment is provided by means of a hand wheel 100 which, by means of screw threads 102, may be manipulated to shift the position of the hollow, tubular member 92.

By means of the mechanism just described, the bearings or supports for the work piece may be quickly and easily adjusted to accommodate pieces of different diameters. Similarly, it will be appreciated that in order to operate on bars of different diameters, or to mill or machine the work piece to different depths, it will be essential that the cutter assemblies be mounted in such a manner that the distance between the cutter faces may be increased or decreased and to this end, as shown in Figure 5, the motors 44, 46 are mounted in frame members 110, 112 which, owing to their shape, may be referred to as "baskets." The inner ends of frame members 110, 112 have bushing portions 114, 116 formed integrally therewith and these bushings have bearings 118, 120 mounted within them for the purpose of supporting the pins 56 which are connected through the coupling 62 to the spindles 64 upon which the cutters 60 are keyed. Adjusting wheels 122, 124 are secured to the frame 28 and are pivotally secured, by means of rods 126, 128 to the basket frames 110, 112 in such a manner that rotation of the wheels shifts the position of the motors and the basket frames about the pivotal points 50 to cause the bearings 118, 120 to move towards or away from one another for the purpose of varying the distance between the cutters 60. Thus the distance between the cutters may be accurately regulated to accommodate work pieces of different sizes or shapes.

For the purpose of affording additional support to the cutters 60 in order to decrease or eliminate vibration, additional bearings 121, 123 are provided and, as shown in Figure 4, these are disposed on opposite sides of the cutters 60 and are arranged to encircle the cutter spindles 64. These bearings are supported in such a manner as to facilitate removal of the cutter assemblies to permit regrinding or replacement and to this end the bearings are carried by plate members 130, 132 (Figure 1) which, by means of bolts 134 and adjusting screws 136 are rigidly secured to decks 138, 140 forming parts of the baskets 110 and 112. In operation, the couplings 62 may be disconnected, following which the plates 130, 132 may be readily removed, carrying with them the spindles 64 and the cutters 60 whereupon new cutters may be installed or the cutters reground and the plates put back on the machine and the couplings connected. At this point it may be mentioned that the bearing assemblies 70 and 72 for the work piece, one of which is shown in Figures 6 and 7, engage the work piece A at locations which may be defined as between the lock-nuts 66 and the bearings 121, 123, there being sufficient room provided at these locations to permit the narrow housing 78, shown in Figure 7, to be accommodated for this purpose.

During the milling operation chips of metal will be removed from the work piece by the cutters 60 and to provide for the removal of these

chips from the machine, a plurality of suction fans 144, 146 are carried by the main frame 28 of the machine for rotation therewith. This arrangement is shown in Figures 2 and 3 in which the motors are provided with intake ducts 150, 152 extending to points in close proximity to the cutters 60 and with discharge ducts 154, 156 leading to points that are remote from the cutters, whereby the suction produced by the fans keeps the machine free of chips and dust. A circular trough, surrounding the machine, or any other suitable arrangement may be provided for receiving the chips as they emerge from the ducts 154, 156. At this point it will be appropriate to point out that the milling operation for which this machine is intended will ordinarily be a dry operation, i. e., one requiring no special lubricant or lubricating system, owing to the fact that the cutters are formed of a carbide material, such as carboloy, and revolve at such high speeds that there is no need for a lubricant.

Turning now to the cutters themselves, as shown in Figures 8 to 12 inclusive, it has already been explained that in accordance with the present invention the cutter is provided with a maximum or near maximum of cutting teeth of minimum or near minimum pitch. The teeth may be in the form of straight lines extending parallel to the axis of the cylinder or they may preferably take the form of a spiral or helical line wound about the cylinder in a manner similar to a screw thread. The pitch of the cutting teeth or blades may vary, of course, depending upon the size of the cutter and the characteristics of the material being milled. By way of illustration, a three-inch steel bar may be satisfactorily milled by means of a cutter having a four inch diameter and a pitch of one-eighth inch. The depth of the teeth may likewise vary but ordinarily it will correspond approximately to the pitch of the teeth, the important consideration being the space between the teeth should be sufficient to receive the chip formed by the action of the cutting edge on the work piece. Both the machine and the cutter disclosed herein are designed and constructed for operation at high speeds: at speeds greatly in excess of those heretofore employed. Thus, if the cutter is made of high-speed steel the blades, in practicing the invention, will move at a speed in excess of 500 feet per minute and if made of carbide materials, or other hard metal such as tungsten carbide, tungsten titanium carbide or carboloy at a speed in excess of 1000 feet per minute. The speed of movement of the cutting tooth or blade may be computed by the formula $\pi d \times R. P. M. = S. F. M.$ Owing to the fact that each tooth or cutting blade has only instantaneous contact with the work piece and is then out of contact therewith for a much longer time than it has been in contact, fatigue or wear of the cutter is reduced to a minimum. Also, owing to the high speed of rotation of the cutter, an infinite number of fine cutting operations are imparted to each small surface area of the work piece, resulting in the production of pieces of greater accuracy and better finish.

The linear speed of the work piece with respect to the cutter cannot be precisely stated owing to the fact that it will depend on such factors as the width of the cutter and the physical characteristics of the work piece but in any event the invention here also contemplates the employment of much higher speeds than heretofore. Thus a three-inch bar may be fed past the carbide cutter at a linear speed of 100 or even 200 feet per min-

ute, an accomplishment heretofore unknown to those skilled in the art.

The cutter may be monolithic in character in which event the teeth or cutting blades will be ground into the exterior cylindrical face of the cutter or it may be built up as, for example, by having the carbide teeth or blades brazed to the cutter body; the important aspect in the design and construction being the low pitch, greater number of teeth and abnormally high speeds. As stated, the pitch of the teeth or cutting edges may vary depending upon such factors as the size of the cutter and the physical characteristics of the work piece, but ordinarily the pitch will lie within the range of from $\frac{1}{64}$ inch to $\frac{1}{2}$ inch. Each individual cutting edge or tooth may be ground or shaped to any desired configuration, to provide clearance, etc., in accordance with the teachings of the prior art.

Although the invention is shown and described herein as embodied in a specific type of machine designed to mill bars, it will be appreciated that the invention, in many of its aspects, may be incorporated in machines of different design and construction. Thus it is contemplated that the bar might be rotated with respect to the cutter, or the bar might be held against lengthwise movement and the cutters arranged to move lengthwise of the bar. Similarly if it is desired to practice the invention on work pieces other than bars, the machine can be designed to accomplish this purpose without departing from the scope of the invention as set forth in the appended claims. Changes and modifications may, of course, be made in the machine illustrated by those skilled in the art, in keeping with the spirit of the invention as herein set forth.

Furthermore, the machine and method, although primarily intended for use in the milling of steel and steel alloys, may have some limited, novel application to non-ferrous metals although it is proper to point out in this connection that non-ferrous metals, such as copper, bronze and the like, being known for their softness have been milled at higher speeds than the so-called hard metals and accordingly the novel method disclosed herein will in some of its aspects be directed to steel and steel alloys but only to the extent required by the prior art.

A typical milling operation which can be satisfactorily performed on the machine may be described as follows: a cutter driven at an R. P. M. of approximately 1500 and having a diameter of approximately 4 inches mills a round bar to a depth of approximately $\frac{3}{2}$ of an inch. The rate of feed between the round bar and the cutter during this operation is approximately 600 inches or 50 feet per minute. This operation is performed, with a cutter having a $\frac{1}{4}$ inch pitch and a $22\frac{1}{2}$ degree helix, on cast iron having a Brinell hardness of 200, or steel of the grade C 1020 having a Brinell hardness of 180. It is to be understood that the helical angle of the teeth may vary but ordinarily it will lie within a range of from 10 degrees to 30 degrees. The teeth themselves may be provided with a radial angle of any desired degree and the cutting faces thereof may, in accordance with the teachings of the prior art, be provided with a desired negative rake angle to assure proper chip disposal.

Finally, although the machine disclosed here-

in is intended primarily for the milling of round bars, it will be appreciated that the invention, including the method, contemplates the milling of other steel and alloy steel products such, for example, as billets, slabs, blooms, rounds, tube rounds, and bars of all shapes as well as apparatus, articles, devices and equipment manufactured from such products.

Having thus described my invention, what I claim as new and desire to secure by Letters Patent of the United States is:

1. A machine for milling metal at high speeds comprising, in combination, a rotary frame; a plurality of frame members pivotally mounted on said rotary frame, a plurality of motors carried by said frame members, a plurality of cutters respectively mounted on said frame members and driven by said motors, means for independently adjusting said frame members about the pivotal

mountings thereof to adjust the position of the cutters with respect to one another, a plurality of bearing assemblies disposed axially of and on opposite sides of the cutters for rigidly supporting the work piece, and means for adjusting the bearings in said assemblies with respect to one another, whereby work pieces of different sizes may be accommodated by the machine.

2. A machine for milling metal at high speeds comprising, a rotary frame, means for rotating said frame, a plurality of frame members pivotally mounted on said frame, a plurality of motors carried by said frame members, a plurality of cutters driven by said motors and respectively mounted on said frame members on opposite

sides of the axis of the work piece to be milled, means associated with each of said frame members for adjusting said frame members about the pivotal mountings thereof to adjust said cutters toward and away from said work axis, a plurality of bearing assemblies located adjacent said cutters and each including work engaging bearing means disposed on opposite sides of said work piece axis for rigidly supporting the work piece against sidewise movement as it is fed through the cutters, and means included in each of said bearing assemblies for simultaneously adjusting the bearing means on both sides of said work piece axis and for independently adjusting the bearing means on one side of said work piece axis relative to the other bearing means to accommodate work pieces of different sizes.

THEODORE S. SEE.
